UNITED STATES PATENT OFFICE.

CALEB M. ANDREWS, OF PROVIDENCE, RHODE ISLAND.

HORSE-BLANKET.

SPECIFICATION forming part of Letters Patent No. 277,867, dated May 22, 1883.

Application filed January 2, 1883. (No model.)

To all whom it may concern:

Be it known that I, CALEB M. ANDREWS, of the city and county of Providence, and State of Rhode Island, have invented a new and useful Improvement in Horse-Blankets; and I hereby declare that the following is a full, clear, and exact description of the same, reference being had to the accompanying drawings, forming part of this specification.

10 This invention has reference to an improvement in horse-blankets.

The object of the invention is to secure the blanket more firmly on the horse and prevent the loss or displacement of the blanket.

15 The invention consists in securing the surcingle to the blanket and to pad the space between the blanket and the surcingle, on each side of the backbone, so as to secure the blanket more firmly, as will be more fully set forth hereinafter.

Figure 1 is a view of a horse-blanket having a surcingle firmly secured, so as to form a part of the blanket. Fig. 2 is a sectional view, showing the surcingle on the outside of the 25 blanket and the padding on each side of the backbone.

In the drawings, A is the horse-blanket.

B is the surcingle, which is firmly secured to the blanket in the oblique position shown 30 in Fig. 1.

C are saddle-pads placed on each side of the center of the blanket, so as to fit the hollows of the back on each side of the backbone. These pads are made of any suitable material, 35 secured between the surcingle and the blanket, so that on securing the blanket they will fit the back of the horse and keep the blanket in place.

Horses are liable, in rubbing, to draw the 40 blanket from under the surcingle, and, by getting one part under their feet, to tear the same. By securing the surcingle to the blanket by sewing or otherwise it holds the same firmly in place, and is not liable to be rubbed off the horse. By securing the surcingle along the 45 whole width of the blanket, and, as is shown, in a diagonal direction, both the surcingle and the blanket will always be placed in the proper position on the horse, the whole forming a more convenient, superior, and more durable 50 article than when constructed separately.

I am aware that horse-blankets have before this been provided with straps secured to the blanket, and also that pads have been secured to the underside of the cover. Such, however, 55 differ from my improved horse-blanket, in that in my blanket, where the surcingle is sewed to the blanket, both are strengthened and every part of the blanket is held firmly by the surcingle, while by placing pads between the 60 surcingle and the blanket the blanket bears closely against the back of the horse and is not raised away from the back by the pads, as in the case where the pads are under the blanket.

Having thus described my invention, I claim 65 as new and desire to secure by Letters Patent—

As an improved article of manufacture, a horse-blanket having a surcingle permanently secured thereto, and having pads interposed and secured between the surcingle and the 70 blanket, as described.

CALEB M. ANDREWS.
